UNITED STATES PATENT OFFICE.

WILLIAM T. PRATER, OF BLOOMFIELD, MISSOURI.

STIRRUP.

1,421,304.

Specification of Letters Patent. Patented June 27, 1922.

Application filed May 10, 1919. Serial No. 296,062. Renewed November 26, 1921. Serial No. 518,073.

To all whom it may concern:

Be it known that I, WILLIAM T. PRATER, a citizen of the United States, residing at Bloomfield, in the county of Stoddard and 5 State of Missouri, have invented new and useful Improvements in Stirrups, of which the following is a specification.

The primary object of the invention is to provide a safety stirrup of that type having 10 a tread plate so connected with the stirrup frame as to enable the horseback rider to obtain a quick release of his foot from the stirrup in case of the animal becoming unmanageable or in case of an accident.

15 Another object of the invention resides in providing a stirrup of the above stated character wherein the latch end of the tread bar, upon the active position of said tread bar, is concealed, thus preventing the rider's 20 foot from accidentally releasing the same from engagement with the latch.

25 A further object of the invention is the provision of a stirrup of the above stated character wherein the tread bar of the stirrup is so constructed as to permit of detachably mounting thereon a foot warming device.

30 A still further object of the invention is the provision of a stirrup of this character, which is simple in construction, serviceable, 35 positive and reliable in its operation and inexpensive to manufacture.

With the above and other objects in view, the invention consists in the novel features, 40 details of construction and combination of parts which will hereinafter be more fully set forth, illustrated in the accompanying drawing and pointed out in the appended claims.

45 Figure 1 is a perspective view of a stirrup constructed in accordance with the invention ready for use;

Figure 2 is a similar view showing the foot tread released;

45 Figure 3 is a view similar to Figure 1, showing the casing in section, illustrating the latch mechanism;

50 Figure 4 is a detail view illustrating the connection of the actuator with the latch bar;

Figure 5 is a perspective view of the tread plate clearly illustrating the manner of attaching thereto my improved foot warming device; and

55 Figure 6 is a transverse section taken through Figure 5.

Referring more particularly to the accompanying drawing, in which like characters of reference refer to corresponding parts in the several views, 5 denotes a metallic frame 60 of substantially U-form presenting parallel limbs 6 and 7 connected to one another through the medium of a curved connecting portion carrying a loop 8 for receiving the usual stirrup strap, not shown, adapted to 65 connect the stirrup to a saddle. The limb 6 of the frame is of hollow tubular formation, providing a casing 9 which is formed in the upper portion thereof with a vertically disposed slot 10, the purpose of which will be 70 fully set forth as the description of the invention is proceeded with.

11 denotes a tread plate with which the rider's foot is engaged when in mounting position, and is provided on its under face 75 with a centrally located reinforcing rib 12, having one end extended beyond the terminal 13 of the tread plate to provide a loop 14. This loop 14 of the reinforcing rib embraces the lower end of the limb 7 for 80 mounting the tread plate thereon for horizontal swinging movement. The free or opposite end of the tread plate is provided on the innermost longitudinal edge thereof and at a point flush with the outer end 15, with 85 an angularly extending foot 16, bent upon the plate and provided with a rearwardly and downwardly extending inclined extension 17, the purpose of which will be hereinafter more fully set forth as the description of the invention is proceeded with. The trunnions 18 and 19 of the operating plate 90 20 are journaled in the openings 21 of the spaced ears 22 formed on the limbs 6 and 7 of the frame, thus disposing the operating 95 plate transversely across the frame 5 for an upward vertical swinging movement, while formed on the lower terminal of the tubular casing 10 is a substantially U-shaped socket 100 23 disposed angularly of the casing and adapted when the tread plate is in locked position, to receive the foot portion 16 thereof, as better shown in Figures 3 and 4 of the drawing. This socket 23 further serves to conceal the foot 16 of the tread plate, and 105 thus prevents the foot of the rider from accidentally displacing the same from the socket.

Disposed in the tubular casing 10 of the frame is a vertically movable latch holder 110 24 adapted when the tread plate is in locked position, to protrude through the aperture

25 of the socket and through the aperture 26 of the foot, thus preventing any accidental releasing of the foot plate from said frame. Encircling the locking bolt 24 is a helical 5 spring 27 tending to exert a downward pressure on the bolt at all times. Carried by the trunnions 18 of the tread plate 20 is an annular extending link 28, said link extending through the slot 10 of the casing and 10 having connection with the latch bolt 24. Thus it will be seen that the engagement of the rider's foot with the plate 20, will rock the link 28 and cause the operation of the latch bolt 24 against the tension of the 15 spring 25, releasing the tread plate 11; when the rider is desirous of releasing his foot from the stirrup, in the event of the animal's becoming unmanageable or having an accident.

20 Detachably mounted on the tread plate 11 is a foot warming device 29. This foot warming device 29 includes a receptacle 30 including a rear wall 31 having end and intermediate notches 32 and 33 respectively, 25 thus allowing the foot warming device to retain in applied position, to clear the flange 34 of the tread plate and the reinforcing rib 12 thereof. The resilient U-shaped clip 35 is provided and is adapted 30 to overlie the tread plate 11 for holding the heating receptacle 30 to the under portion of said tread plate, and to this end, the limbs of said clip are provided with flanges 36 which engage under the flange 34 of the 35 tread plate and hold the heating receptacle to the tread plate and further retain the protector 37 upon the upper face of the tread plate. This protector is preferably in the form of a sheet of asbestos and prevents 40 any injury to the foot of the rider.

From the foregoing description, taken in connection with the accompanying drawing, the advantages of construction and of the method of operation will be readily apparent to those skilled in the art to which the

invention relates, and while I have described the principles of operation of the invention, together with the device which I now consider to be the best embodiment thereof, I desire to have it understood that the device 50 shown is merely illustrative, and that such changes may be made when desired as are within the scope of the claims appended thereto.

I claim:

1. A safety stirrup embodying a frame, a casing supported thereon having a socket, a tread plate mounted on the frame for horizontal swinging movement, an upstanding foot carried by said tread plate and adapted to engage in the socket of the casing in the operative position of said plate, a latch bolt mounted in said casing for locking the tread plate therein, and means supported on the frame and having connection with the upper end of the latch bolt for causing the release of said bolt from said plate.

2. A safety stirrup embodying a U-shaped frame, a tread plate pivotally connected to the frame for horizontal swinging movement, means for locking the said tread plate in foot engaging position, a plate mounted upon the frame for rocking movement and provided with a trunion, a link on said trunion, said links having connection with the said locking means for actuating the same to release the tread plate, substantially as and for the purpose specified.

3. A safety stirrup embodying a frame, a latch supported on the frame, and a tread plate supported on the frame for horizontal swinging movement, said tread plate being formed with a reinforcing rib, a foot on the tread plate having an inclined extension, said extension upon the closing of the tread plate adapted to engage with the locking means for lifting the same to permit the said plate to be swung to closed position.

In testimony whereof I affix my signature.

WILLIAM T. PRATER.
